UNITED STATES PATENT OFFICE.

ALAN ERNEST LEOFRIK CHORLTON, OF WESTMINSTER, LONDON, AND JOHN SALMOND DOIG, OF GRIMSBY, ENGLAND, ASSIGNEES OF ONE-THIRD TO SIR WILLIAM BEARDMORE, OF WESTMINSTER, LONDON, ENGLAND.

POWER APPARATUS FOR USE ON VESSELS.

Application filed October 19, 1920. Serial No. 418,063.

To all whom it may concern:

Be it known that we, ALAN ERNEST LEOFRIK CHORLTON, C. B. E., and JOHN SALMOND DOIG, subjects of the King of England, and residing, respectively, at Westminster, London, in England, and Grimsby, Lincolnshire, in England, have invented certain, new and useful Improvements in Power Apparatus for Use on Vessels, of which the following is a specification.

This invention relates to power apparatus for use on vessels more particularly vessels of the trawler type wherein the power required for operating the winch or other apparatus when considered in relation to the power required for propulsion is larger than in other cases and has for its object to enable internal combustion engines to be employed on these vessels both for propulsion and for driving a winch, windlass or other machine at the same time.

According to this invention an internal combustion engine is employed which comprises several cylinders some or all of which can be employed for the purpose of propulsion while one or more of these cylinders are separately usable for applying power to a winch or other like mechanism or for driving an air compressor, dynamo or other machine. The whole engine is divided by arranging the cylinders in groups and the pistons in the cylinders operate upon a crank shaft which is similarly divided and the parts of which can be coupled or disconnected by means of clutches. The cylinders are so grouped and the crank shaft and clutches so formed and arranged that either the power obtainable from all the cylinders may be utilized for driving the propeller shaft or only one or certain of the cylinder groups may be so used while the remaining cylinders or one or more of the groups supply power for operating or driving a winch or other machine. Thus for example in the case of a six-cylinder engine which is divided into two cylinder groups the pistons in four of the cylinders are connected to a length of crank shafting which is coupled to the propeller shaft while the pistons in the remaining two cylinders are connected to a further length of crank shaft at each end of which is a clutch so that this part of the shaft may be either coupled to the main part of the crank shaft and through

it to the propeller shaft or alternatively the second part of the crank shaft may be disconnected from the main part of the crank shaft and coupled to mechanism by means of which a winch or other machine can be driven.

In some cases more particularly where a winch is to be driven by the engine a variable speed transmission mechanism is interposed between the clutch at the forward end of the crank shaft and the winch.

With an engine thus arranged it is convenient to employ a propeller of the feathering type so that when it is desired to reduce the speed of propulsion the revolutions of the engine can be maintained substantially constant while the propulsive effort is varied by means of the propeller. It may also be convenient to provide a reversible rudder.

The Diesel or semi-Diesel type of engine is conveniently employed but other types of internal combustion engine can also be utilized in the manner indicated. The grouping of the cylinders, that is to say the manner in which the total available power is divided so that the parts may be used separately or together, may vary. For example there may be three groups comprising say four cylinders in the main engine which is directly coupled to the propeller shaft, while there may be one, two or more cylinders in each of two or more other groups. With such an arrangement when the winch is to be operated the main group of engines alone may continue to supply power for propulsion when one or more of the other groups may be coupled up for supplying power to the winch. The fore or lesser cylinder group may advantageously be used as a starting engine for the main part of the engine as well as being available for the other purposes indicated.

If the other mechanism for which the power is obtained from one or more cylinder groups is for example a dynamo, this mechanism may be driven through a clutch from the forward end of the crank shaft but in the case of mechanism of other types, but more particularly a winch, a variable speed transmission mechanism is conveniently employed between the winch and the clutch at the forward end of the crank shaft. It is desirable to provide in conjunction with this transmission mechanism some safety

device which in the case of a winch will yield or prevent straining of the parts in the event of an overload on the winch. The nature of such safety device may vary as found desirable and may comprise for example a slipping control device suitably disposed in the transmission mechanism.

The several clutches by means of which the parts into which the whole engine is divided can be coupled together and suitably controlled and operated and the construction of these clutches may be on some known lines. The details of construction may be modified as found desirable in accordance with the type of vessel to which the invention is applied and to suit the winch or other mechanism which is to be operated.

The accompanying drawings illustrate diagrammatically two alternative constructions of power apparatus in accordance with the present invention. In these drawings—

Figure 1 represents a longitudinal sectional elevation of one arrangement of the power apparatus disposed in a vessel the engine being available for propulsion and also for driving a dynamo.

Figure 2 is a similar view showing an arrangement of the apparatus where the engine is used for propulsion and also for the driving of a winch.

Like letters indicate like parts throughout the drawings.

Referring to Figure 1 the engine is of the Diesel or semi-Diesel type and has the cylinders arranged in two groups. In one of these groups A there are four cylinders while in the other group B there are two cylinders. The cylinder group A has its part C of the crank shaft directly coupled at one end to the propeller shaft D. At the other end of the part C of the crank shaft is a clutch E by means of which the shaft C can be coupled to one end of the crank shaft part F of the second cylinder group B. At the forward end of this crank shaft part F is a clutch G by means of which the crank shaft can be coupled to the shaft of a dynamo H.

The propeller J may be of the feathering or variable pitch type constructed on known lines and controlled by mechanism mounted as at K.

If it is desired to utilize full power for driving the propeller J the clutch E is engaged so as to couple the crank shaft parts C and F and the clutch G is disengaged. If the clutch E is disconnected the propeller will be driven by the cylinders comprised in group A while the cylinders in group B can be utilized to drive the dynamo H when the clutch G is engaged. If desired by means of a variable pitch propeller such, for instance, as disclosed in the patent to Henry Barcroft, No. 431,428, dated July 1, 1890, the propulsive effort can be modified while

maintaining substantially constant the revolutions of the engine.

Referring to Figure 2 the construction and arrangement of the engine with two groups of cylinders A and B and a divided crank shaft CF together with a variable pitch propeller J coupled to the after end of the crank shaft and the clutches E and G is substantially as described with reference to Figure 1. In this instance, however, at the forward end of the part F of the crank shaft and beyond the clutch G there is arranged a variable speed transmission mechanism L of some suitable type and construction which can be coupled to the part F of the crank shaft by the clutch G. The driven member of the variable speed mechanism L carries a bevel wheel M which gears with a bevel wheel M' mounted on the end of vertically disposed shafting N. This shafting N at its upper end drives through gearing a winch H' of suitable type. In the length of shafting N there is preferably disposed a safety device N' of some known construction which may comprise for example a slipping control and this device serves to prevent damage to the mechanism in the event of an overload on the winch H'. The variable speed mechanism L is conveniently controlled by a hand lever L' disposed on the deck O of the vessel adjacent to the winch H'.

The arrangement is such that if the whole engine power is required for propelling purposes the part F of the crank shaft belonging to the engine group B is coupled to the crank shaft part C which belongs to the main engine group A by means of the clutch E, the clutch G being disconnected. If, however, power is required for driving the winch H' at the same time that power is wanted for propulsion the clutch E is disconnected and the crank shaft part F is coupled to the variable speed mechanism L by means of the clutch G. If desired power from the main engine group A may also be used for operating the winch if the portions C and F of the crank shaft are coupled by the clutch E and if the blades of the propeller J are adjusted so as to reduce or eliminate the propulsive effort.

The mechanism by means of which the winch H' is operated may vary in accordance with requirements as also the position in which this winch is disposed with relation to the engine.

Cylinders grouped and operating on a divided crank shaft in the manner described may be utilized in various ways and for various purposes.

What we claim as our invention and desire to secure by Letters Patent is:—

1. In power apparatus for use on vessels, in combination, an internal combustion engine comprising a plurality of cylinders ar-

- arranged in groups, a crank shaft divided in accordance with the grouping of the cylinders, means for detachably coupling the sections of the crank shaft together, work performing means at the opposite ends of the crank shaft, and mechanism associated with each of said work performing means whereby the amount of work performed thereby may be varied or rendered negligible so that the power of all the cylinders may be utilized by either work performing means or any fraction thereof utilized by either such means.
2. In power apparatus for use on vessels, in combination, an internal combustion engine comprising a plurality of cylinders arranged in groups, a crank shaft divided in accordance with the grouping of the cylinders, means for detachably coupling the sections of the crank shaft together, a propeller at one end of the crank shaft and a rotatable work shaft at the other end of the crank shaft, mechanism associated with the propeller and mechanism associated with the rotatable shaft whereby the amount of work performed by each may be varied or rendered negligible so that the power of all the cylinders may be utilized by either the propeller or work shaft in performing work or any fraction thereof utilized by either such means in performing work, said first mentioned mechanism comprising a device for altering the pitch of the propeller and said second mentioned mechanism comprising a variable speed device interposed between the crank shaft and work shaft.
- In testimony whereof we have signed our names to this specification.
